UNITED STATES PATENT OFFICE.

JAMES KEISTER, OF STEUBENVILLE, OHIO.

REVERSIBLE FOUR-CYCLE ENGINE

1,237,054.

Specification of Letters Patent. Patented Aug. 14, 1917.

Application filed June 8, 1917. Serial No. 173,520.

To all whom it may concern:

Be it known that I, JAMES KEISTER, a citizen of the United States, and a resident of Steubenville, in the county of Jefferson and 5 State of Ohio, have invented a new and Improved Reversible Four-Cycle Engine, of which the following is a full, clear, and exact description.

This invention relates to four-cycle engines of that type which includes a reciprocating sleeve valve in the cylinder and surrounding the piston for controlling the inlet of the fuel charges and the outlet of the exhaust gases, such an engine being shown 10 in United States Letters Patent 1,144,208, granted to me June 22, 1915.

The object of the present invention is to so improve an engine of this character that it can be easily reversed, this being accomplished by controlling the circuit breaker of the ignition system.

A more specific object of the invention is to provide ports in the sleeve valve in such relation to the ports in the engine cylinder 25 that the ports are thrown into or out of register simultaneously and automatic check valves are arranged in the inlet and outlet conduits, and in combination with this arrangement of ports and valves is used an ordinary circuit breaker which is so manipulated that the times of ignition can be adjusted to cause the engine to be reversed.

With such objects in view, and others which will appear as the description proceeds, the invention comprises various novel features of construction and arrangement of parts which will be set forth with particularity in the following description and claims appended hereto.

40 In the accompanying drawing which illustrates one embodiment of the invention and wherein similar characters of reference indicate corresponding parts in all the views,

45 Figure 1 is a central longitudinal section of an engine, showing the piston on its suction stroke; and

Figs. 2 and 3 are detail views of the circuit breaker, showing the different positions for forward and reverse running.

50 Referring to the drawing, A designates the engine cylinder having a reentrant head 1 and the walls of the cylinder are provided with inlet and exhaust ports 2 and 3 respectively. In the inlet conduit 4 is a check valve 5 of any suitable form which opens toward the engine so that the fuel mixture

can flow to the cylinder. An exhaust conduit 6 connected with the port 3 has a suitable check valve 7 which opens outwardly or away from the engine cylinder. Slidable in the cylinder is a sleeve valve 8 which is provided at diametrically opposite points with ports 9 and 10 which are adapted simultaneously to register with the ports 2 and 3. In the sleeve valve is the piston 11 connected by a rod 12 with the crank pin 13 of the crank shaft 14. The crank shaft is connected by a half speed reduction transmission 15 with a crank 16 that is connected by a link 17 with the sleeve valve 8 so as to 60 reciprocate the same in timed relation with the piston.

When the piston moves outwardly, as shown in Fig. 1, the fuel charge is drawn in through the check valve 5, which automatically opens, the suction operating on the check valve 7 to hold the same closed. On the next in stroke the charge will be compressed, since in the meantime the sleeve valve will close the ports 2 and 3 by the 70 ports 9 and 10 passing out of registry therewith. After the charge is compressed the spark plug 18 ignites the charge and the exploded gases force the piston outwardly. At the end of this out stroke the sleeve valve 8 brings its ports 9 and 10 into registry with the ports 2 and 3, so that the exhaust gases can be forced by the inwardly-moving 80 piston out through the ports 10 and 3 and past the valve 7, the valve 5 being held 90 seated by the pressure of the exhaust gases thereon.

The circuit breaker (Figs. 2 and 3) includes a cam 19, which in the usual manner is operatively connected with the crank 95 shaft and it engages a roller 20 on the pivoted arm 21 which carries a contact 22 engageable with the contact 23. This contact 23 is mounted on a carrier 24 formed with an arm 25 which is operatively connected 100 with the controlling lever of the engine. The neutral or dead central position of the circuit maker is indicated by the dotted line a, while the lines b and c are the two 110 different running positions.

When the engine is running in a clockwise direction the spark may be advanced by moving the lever 25 toward b, thereby giving the engine greater velocity and efficiency. When the engine is thus running it can be reversed by moving the lever 25 from an advanced spark position toward

the position *a*, so as to retard the engine, and now the lever is quickly moved toward *b* again, which will so advance the spark that the engine will reverse. To 5 start the engine in an anti-clockwise direction from a state of rest the lever 25 is placed at position *b*, and the engine started in the conventional way. When the engine is started the lever is moved toward *c*, so 10 as to advance the spark and increase the speed. It will thus be seen that the engine may be reversed, accelerated or retarded in either direction by the manipulation of the spark lever.

15 From the foregoing description taken in connection with the accompanying drawing, the advantages of the construction and method of operation will be readily understood by those skilled in the art to which 20 the invention appertains, and while I have described the principle of operation, together with the device which I now consider to be the best embodiment thereof, I desire to have it understood that the device 25 shown is merely illustrative and that such changes may be made when desired as fall within the scope of the appended claims.

Having thus described my invention, I claim as new and desire to secure by Letters 30 Patent:

1. In an engine, the combination of a cylinder having inlet and exhaust ports, a sleeve valve in the cylinder and having ports adapted simultaneously to register with the

first-mentioned ports, a piston in the sleeve 35 valve, operating connections between the piston and valve for moving the valve at half the speed of the piston, a check valve at the inlet port and opening toward the cylinder, and a check valve at the exhaust port 40 and opening away from the cylinder.

2. In an engine, the combination of a cylinder having inlet and exhaust ports, a sleeve valve in the cylinder and having ports adapted simultaneously to register with the 45 first-mentioned ports, a piston in the sleeve valve, operating connections between the piston and valve for moving the valve at half the speed of the piston, a check valve at the inlet port and opening toward the 50 cylinder, and a check valve at the exhaust port and opening away from the cylinder, with a circuit breaker operatively connected with the engine, and an ignition device whereby the engine may be reversed, ac- 55celerated or retarded in either direction.

3. The combination of a cylinder having ports at diametrically opposite points for the admission and exhaust respectively, a sleeve valve having ports at diametrically 60 opposite points, check valves for the admission and exhaust ports, respectively, a piston in the sleeve valve, and an operating connection for moving the ports of the sleeve valve into and out of registry with 65 the ports of the cylinder.

JAMES KEISTER.
